US0D1003107S

(12) **United States Design Patent** (10) **Patent No.:** **US D1,003,107 S**
(45) **Date of Patent:** **** Oct. 31, 2023**

(54) **CONTAINER LID**

(71) Applicant: **TRRS MAGNATE, LLC**, Manteca, CA (US)

(72) Inventor: **Thomas Anthony Raymus**, Manteca, CA (US)

(73) Assignee: **TRRS MAGNATE, LLC**, Manteca, CA (US)

(**) Term: **15 Years**

(21) Appl. No.: **29/885,472**

(22) Filed: **Feb. 24, 2023**

(51) **LOC (14) Cl. 07-02**

(52) **U.S. Cl.**

USPC **D7/392.1; D9/449**

(58) **Field of Classification Search**

USPC D7/507, 509, 510, 511, 514, 523, 532, D7/533, 535, 536, 392.1, 396.1, 396.2, D7/608; D3/202; D9/435, 443, 446, 449

CPC B65D 1/40; A47G 21/18; A47G 19/22; A47G 19/2288; A47G 19/2205; A47J 41/0055; A47J 41/00; A47J 41/0077; A47J 41/0088; A47J 43/27; Y10S 220/903

(57) **CLAIM**

The ornamental design for a container lid, as shown and described.

DESCRIPTION

FIG. 1 is a perspective view of my new design for a container lid;

FIG. 2 is a first side view thereof;

FIG. 3 is a second side view thereof;

FIG. 4 is a third side view thereof;

FIG. 5 is a fourth side view thereof;

FIG. 6 is a top view thereof;

FIG. 7 is a bottom end view thereof;

FIG. 8 is a perspective view thereof in a first alternate position;

FIG. 9 is a perspective view thereof in a second alternate position within a water bottle environment; and,

FIG. 10 is a side view thereof in a second alternate position within a water bottle environment.

The portions of the container lid shown in broken line form no part of the claimed design. The broken line showing of a bottle in FIGS. 9 and 10 depicts environmental subject matter and forms no part of the claimed design.

1 Claim, 10 Drawing Sheets
